ASSEMBLING MACHINE AND METHOD

John C. Gibbs, Brooklyn, N. Y., assignor to
Anchor Cap & Closure Corporation, Long
Island City, N. Y., a corporation of New York

Application May 17, 1932, Serial No. 611,827

26 Claims. (Cl. 113—1)

The present invention relates to the art of manufacturing closure caps, cans and similar articles, and particularly to an assembling machine and method for assembling the parts of such articles.

Without any intention of limiting the scope of the present application to the closure, to the machine, or to the minor details described, a preferred embodiment of the invention illustrating a particular application thereof, will be described in detail. It will be understood, however, that the invention may be applied to the manufacture of certain types of cans, or other articles of similar nature.

In the manufacture of closure caps, cans and the like, tin plate is customarily used and is lacquered while in flat sheets before being made into the desired articles. It is not feasible to draw such coated tin plate into deep cup-shaped blanks without rupturing the lacquered coating and also the tin coating of the sheet material. If an article such as a ketchup cap is drawn from a single piece of metal, the brilliancy of the lacquer is impaired, the lacquer coating is ruptured and the metal is exposed. When applied to ketchup bottles, the product reacts chemically with the exposed metal and discoloration and corrosion result. The drawing operation is so severe that the drawn blanks have to be inspected and many of them thrown out.

At the present time, probably ninety per cent, or more, of the ketchup caps sold are made in two pieces. Cans are, likewise, made in two pieces to avoid the drawing operations, and the resulting distortion of the articles. An example of a modern ketchup cap may be found in the patent to Robert A. Russell, No. 1,327,967, dated January 13, 1920. In this patent, the top of the button is secured to the body by an interfolded seam at one end thereof, and the ends of the body are secured together by an interfolded longitudinal seam extending along the side thereof.

These two-piece caps lend themselves particularly to attractive decorations, because neither the body part nor the button is distorted materially in the manufacture thereof. It is customary to decorate both the body part and the button prior to the assembly thereof. Ordinarily, the button is made of a contrasting color and has some form of printing thereon, for example, the name of the packer.

The seam extending longitudinally at the side of the body part is somewhat unsightly and is particularly objectionable in small articles such as closure caps. The interfolded portion of the

seam has four thicknesses of metal, whereas the rest of the body is of single thickness. For this reason, many packers desire to conceal the seam in the body by having it always on the side of the bottle, opposite to the label, so that one looking at the label of the bottle does not see the seam of the cap. This may be done by a proper relation between the thread in the cap and the thread on the button. In addition, packers require that the button, or end, of the cap be positioned in the body so that one looking at the label of the bottle will be able to read the printed matter on the button without having to turn the bottle around. The advantage of having the button positioned in the cap is sufficient to warrant payment by the packer of the extra cost for positioning the buttons in the caps, even where such work has to be done manually.

Many of the packers desire the buttons to be positioned in the caps, but are unwilling to pay the additional cost thereof. It is, therefore, important to provide an inexpensive machine and method, which will position the button with respect to the seam of the body part. It is, likewise, important that the attachment for performing this function be applicable to present machines for assembling the parts of closure caps, with a minimum number of changes in such machines.

The present machine and method are improvements upon the machine and method illustrated in the James Hardiman Patent No. 1,881,533, dated October 11, 1932, and are designed particularly to simplify the machine and to avoid interruptions in operation due to the failure of the parts to function in their proper manner.

An object of the present invention is to provide a simple, inexpensive machine and method for assembling the parts of an article in a predetermined relation to each other.

Another object of the invention is to provide a machine and method which will accurately position a button for a body part with respect to the seam in the body part.

Another object of the invention is to utilize an indentation in the periphery of the button to position the decoration thereon with respect to the seam of a body part.

Another object of the invention is to provide a simple machine and method for rotating the button or end portion into proper position with respect to the seam of the body part.

Another object of the invention is to utilize a partial vacuum for holding the button or end

30

- portion during its rotation into proper position with respect to a body part.
- Another object of the invention is to provide a continuously rotating mandrel for inserting a button into a body part.
- Another object of the invention is to provide a mechanism for accomplishing the foregoing objects, which is readily applicable to existing machines used in the manufacture of such articles.
- Another object of the invention is to increase the speed and certainty of operation in a mechanism adapted to achieve the above objects.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein

Fig. 1 is a top plan view of a machine for assembling the parts of a closure cap or similar article, showing a preferred embodiment of the present invention applied thereto;

Fig. 2 is a diagrammatic illustration of the steps in the assembling of the parts of a closure cap in accordance with the present invention;

Fig. 3 is a perspective view of the finished cap;

Fig. 4 is a fragmentary side elevational view illustrating the button feeding mechanism;

Fig. 5 is a fragmentary front view illustrating the button feeding mechanism;

Fig. 6 is a fragmentary sectional view on line 6—6 of Fig. 1, with the mandrel about to engage a cap, illustrating a preferred embodiment of a mechanism for engaging and rotating the buttons or ends;

Fig. 7 is a sectional view along the line 7—7 of Fig. 6;

Fig. 8 is an enlarged sectional view of a portion of Fig. 6;

Fig. 9 is an enlarged sectional view on the line 9—9 of Fig. 8;

Fig. 10 is a sectional view similar to Fig. 8, with the button inserted into the body part of the cap;

Fig. 11 is a sectional view on the line 11—11 of Fig. 10;

Fig. 12 is a sectional view on the line 12—12 of Fig. 8, illustrating the mechanism for holding the button in proper position; and

Fig. 13 is a fragmentary sectional view of a preferred chuck for connecting the buttons to the body parts.

Referring again to the drawings, and particularly Figs. 2 and 3 thereof, there is shown a two-piece closure cap which the present embodiment of the invention is particularly useful in making. The cap, or article, comprises an end portion 1, which is termed herein a button. The button has an upstanding flange 2 and a recess or indentation 4 in the outer periphery of the flange for purposes which will be described hereinafter. The button is to be assembled with a body part 5, which may be made by bending a strip of metal into a cylindrical form and joining the ends thereof by an interfolded seam, as shown at 6. The button is generally decorated, either with a design or with a suitable legend or trade-mark, as illustrated in the drawings, and it is desirable to have the top of the legend at

the seam 6 of the body part, so that one reading the legend will observe the side of the body part which is free from seams, as shown more particularly in Fig. 3. The present invention aims to provide a simple machine and method adapted to turn the button, during the assembling operation, into proper registry with the body part so that the legend on the surface thereof will be positioned with respect to the seam on the body part.

Referring more particularly to Fig. 1, a machine is shown for automatically assembling the parts of a closure cap. At the center of the machine is a turret 7 having a number of body supporting members 8. At the left of the turret is a horn mechanism 9, which receives blanks 3 of material, folds them into cylindrical body parts, and places them on the supporting members 8 of the turret. The turret moves, step by step, and delivers the body part 5 to an assembly station at 10, where a button 1 is assembled in the body part. Thereafter, the turret moves the body part, with the button in it, around to the chuck 11, (Fig. 13) which forms an interfolded seam 13 between the button and body part. The turret then delivers the assembled cap to a take-off station 12, where it is dropped into a chute 14 and delivered to a suitable thread rolling machine.

If desired, the entire machine may be driven by a belt 15 adapted to rotate a pulley 16 on a shaft 17, which is connected to the horn mechanism 9 and carries a bevel gear 18 adapted to mesh with a bevel gear 19, on shaft 20, to drive the chuck mechanism 11 through bevel gears 21 and 22. It is not believed necessary to describe these mechanisms in detail, since the present invention is more particularly concerned with a mechanism for turning and inserting the button into the body part, and since the machine described generally above is found in the plant of the assignee herein, at Long Island City, New York.

Referring more particularly to Figs. 4 and 5, a mechanism is shown for feeding the buttons, which are preferably hopped and delivered to a chute 25, with the flange of the button extending away from the body part of the cap. The chute is substantially vertical and the buttons are fed one at a time by means of a pair of pins 26, attached to a rocker arm 27. When the rocker arm 27 is operated to withdraw the upper pin 26, the button drops down on the lower pin, as indicated in Figs. 4 and 5. When the rocker arm 27 is operated to insert the upper pin 26, the buttons above the lower one are supported and the lower pin 26 is automatically withdrawn to drop the bottom button. While any suitable means may be utilized for operating the rocker arm 27 and the pins 26, they are shown herein connected by means of an arm 28 and link 29 to lever 30, which is pivoted at 31. The lever 30 has an extension 32 in the path of the body parts, supported by the turret 7, so that, as each body part passes the member 32, the lever 30 is depressed and the rocker arm 27 is oscillated to release a single button to be assembled with the body. A set screw 34 regulates the upward movement of the lever 30, which is retained in its upper position by a spring 35.

The mechanism for turning the button into proper registry with the body part, and for assembling the button with the body part, will now be described. The body part 5, shown in dot-dash lines in Fig. 8, is supported by the turret 7 at the assembling station 10. The button 1 is dropped, by means of the feeding mechanism described

above, into the position shown in Figs. 6, 8 and 9. The mechanism for engaging and inserting the button into the body part of the cap is shown more particularly in Figs. 6 to 12. Referring more particularly to Fig. 6, there is shown a hollow member or mandrel 36, one end of which terminates adjacent the guideway 25, for feeding the buttons; the other end of which is connected to a source of suction 37, through a packing gland 38. The mandrel 36 is supported at one end in a bearing 39 having a suitable bushing 40, and at its other end in a bearing 41 having a bushing 42. The mandrel 36 is rotatably mounted in these bearings and also longitudinally movable therein. A pulley 44, keyed to one end of the mandrel 36, is adapted to be driven continuously by a belt 45 and pulley 46 (Fig. 1). The pulley 46 is mounted on shaft 47, which is connected through pulleys 48 and 49 and belt 50, directly to the drive 20 for the entire machine. It will be understood that any other suitable means may be utilized for continuously rotating the mandrel 36, but the mechanism described is preferred because it does not require a separate source of power and, in addition, the belt 45 may be regulated so that there is a desired amount of slippage, but such slippage is not necessary to the proper operation of the machine.

Referring again to Fig. 6, there is shown a cam 52 keyed to shaft 20, operatively connected to the drive of the machine through bevel gears 18 and 19, which operates a bell crank 54, pivoted at 35, having a cam roller 56 at one end, held against a cam 52 by a spring 57, and attached, at 35 its other end, to the mandrel 36 by means of a bushing 58 and nuts 59. The upper end of the bell crank 54 is forked to extend about the sides of the bushing and to engage the nuts 59 to reciprocate the mandrel 36 for inserting the buttons into the body parts. The bearing 41 has a slot 61 registering with the guideway 25 for the buttons, so that a button may be dropped into the bearing 41 adjacent the end of the mandrel 36. The bearing 41 is keyed against rotation by means of the pin 62, fitting into a slot 64 in the flange of the bearing 41, but is adapted to reciprocate, under the influence of a spring 65, when the mandrel 36 is reciprocated for inserting the buttons into the body parts of the caps. The outer end of the bearing 41 has a cylindrical bore 66, leading to a shoulder 67, which is adapted to telescope over the supported body parts when the mandrel 36 is moved forward. The end of the mandrel 36 is preferably provided with a gasket 69, held in position by a threaded member 70 having a central bore therein connecting with the hollow mandrel 36. A suitable washer 71 may be interposed between the gasket 69 and the end of the mandrel and may be sufficiently large 60 in diameter to abut against the bushing 42.

When a button 1 is fed through the slot 61 of the bearing 41 to a point adjacent the end of the mandrel 36, the suction of the bore of the mandrel draws the button against the end of the mandrel and into engagement with the gasket 69. Since the mandrel is rotated continuously by the pulley 44, the button engaged thereby is also rotated continuously. The force tending to rotate the button is controlled entirely by the extent of the vacuum and the friction between the button and the gasket 69.

In order to stop the rotation of the button when it has been turned into proper registry with the body part of the cap, there is provided a recess 4 in the periphery of the button, as de-

scribed above. This recess contacts with a key member 72. The key member is mounted upon a pin 74 extending longitudinally thereof, permitting the key to oscillate from full line position to dotted line position, as shown in Fig. 9. A flat spring 75 extends through the end of the pin, as shown more particularly in Figs. 8, 10 and 12, to maintain the key 72 in the full line position shown in Fig. 11. When the button 1 is rotated, the recess 4 thereon engages the pin 72 and moves it over from the full line position shown in Fig. 9 to the dotted line position, where the key engages an abutment which definitely holds the pin 74 against further rotation. From then on, the gasket 69, against which the button is held by 15 vacuum, slips on the button and the button is held in proper registry with the body part of the cap. Immediately when the button is removed, the spring 75, resting at its respective ends on the supports 76, retains the key 72 resiliently in 20 position to be engaged by the recess 4 of the succeeding button. The key 72 is of substantial length, and continues to engage the recess in the button until the button has been inserted into the body part of the cap, where the friction between the body part and the button usually exceeds the friction between the gasket and the button and retains the cap against rotation. Preferably, the suction is cut off from the mandrel when the mandrel is moved forward a pre-determined distance, so that the friction between the gasket 69 and the button 1 will be substantially decreased when it is no longer desired to turn the button.

While the preferred embodiment contemplates 35 the use of the key 72 for causing the button to register properly with respect to the seam of the body part of the cap, the seam in the body part may be utilized in the present mechanism for engaging the recess 4 in the cap to hold it against 40 rotation. Due to the four thicknesses of metal at the seam 6 (Fig. 11), the seam extends slightly radially inwardly from the body part of the cap, thus providing a suitable stop for engaging the recess 4. Where the seam is utilized to stop the 45 button, it would be desirable to have the friction between the gasket 69 and the button greater than the friction between the button and the body part so that the button would turn until the recess 4 engaged the seam 6 of the body 50 part. This would make it unnecessary to use the key 72, but would make it desirable to assemble the button and the body part with the recess 4 adjacent the seam 6. With the present mechanism, the recess 4 may be positioned at, or any 55 desired distance from, the seam 6.

In the operation of the machine, the strips of metal or blanks 3 (Fig. 1) are fed into the horn 9, either manually or automatically, which bends the strips into cylindrical forms and secures the 60 edges together to form the body parts. The horn delivers these body parts to, and places them upon, the supports 8 of the turret 7. The turret rotates, step by step, to position the respective supports 8 and body parts 5 in front of the chute 25 and mandrel 36 (Figs. 6 to 12). The rocker arm 21 and pins 26 are operated by the body part 5, engaging the extension 32 in its movement (Figs. 1, 4 and 5) to drop a button through the slot along the guideway 25, through 65 the slot 61, into the bearing 41. The suction through the hollow mandrel 36 draws the released button against the gasket 69 at the end of the mandrel, where it is held. The mandrel 36 is rotated continuously by the pulley 44 and belt 75

45, connected to the drive of the machine, which in turn rotates the button held by vacuum on the end of the mandrel. The key 72, held in position by a flat spring 75, engages the recess 4 5 in the periphery of the button to hold the button against further rotation when it has been turned into proper registry with the body part of the cap. Thereafter, the mandrel 36 is moved axially by means of the cam 52 on drive shaft 20 10 and bell crank 54, to insert the button into the body part. The key 72 continues to hold the button during its longitudinal movement until it is actually delivered to and inserted into the body part of the cap, at which time the friction between 15 the body part of the cap and the button thereof is sufficient to retain it against further rotation. To avoid any chance of the cap being rotated beyond its proper position after it is released by the key 72, the vacuum is cut off from 20 the mandrel 36 and atmospheric pressure is admitted thereto when the mandrel reaches a predetermined position, preferably at about the time that the button disengages the key 72 and engages the body part of the cap. A suitable aperture 33 (Fig. 6) may be utilized for releasing the 25 vacuum within the mandrel. This aperture will be automatically uncovered when the mandrel is moved a predetermined distance inwardly. When the mandrel 36 is moved inwardly to insert 30 the button into the cap, the bearing 41 is likewise moved, under the influence of the spring 65, until the outer bore 66 thereof telescopes about the body part of the cap so that the body part engages the shoulder 67 and forms substantially a continuation of the inner bore of the bearing. This facilitates the insertion of the button into the body part. The distance that the body part may be inserted is definitely determined by means of the end of the support 8, 35 against which the button is pressed by the mandrel 36. After the button has been inserted into the body part, the mandrel 36 is withdrawn, by means of the cam 52, bell crank 54 and spring 57, and the atmospheric inlet 33 will be automatically covered and suction applied to the interior of the mandrel.

Referring again to Figs. 1 and 13, the assembled button and body part are moved around to the chuck 11, which engages the upper end of the body part 5 and folds it over the flange 2 of the button. Preferably, the chuck 11 moves axially with respect to the body part, so that the upper end of the body part is pressed radially inwardly and downwardly to interlock with the flange 2. The completed cap is then discharged by means of a pin 80 engaging the button thereof, and dropped into the chute 14, where it may be delivered to a threading machine, or other mechanism, for applying a rolled wire edge at its bottom and suitable screw threads in the body part for engaging a container.

It will be seen that the present invention provides a very simple method and machine for turning buttons into proper registry with the body parts of closure caps or similar articles. The turning mechanism may be readily attached to existing machines, thereby eliminating the necessity of discarding present equipment. The 65 mechanism is made from a minimum number of parts and these parts are not likely to become disarranged or to give any material trouble to the operator. The buttons may be made to register with the body parts without any additional 70 labor in the manufacture of the caps and, hence,

packers may be supplied with a better product without increase in the manufacturing cost.

As various changes may be made in the form, construction and arrangement of parts herein without departing from the spirit and scope of the invention and without sacrificing any of its advantages, it is to be understood that all matter herein is to be interpreted as illustrative and not in a limiting sense. While the preferred embodiment is described with specific reference to closure caps, it will be understood that the invention is applicable to the manufacture of various articles, where registering of the parts is advantageous.

Having thus described my invention, I claim: 15

1. The method of assembling decorated buttons with body parts, which method comprises applying a force tending to rotate the button continuously, holding said button against rotation when turned into proper position, and interlocking said button and said body part. 20

2. The method of assembling buttons with seamed body parts, which method comprises applying a force tending to rotate a button having a recess in the periphery thereof continuously, 25 utilizing said recess to stop the rotation of the button when in proper position and inserting the button into a body part.

3. The method of assembling buttons with body parts in a definite relation to each other, 30 which method comprises applying rotative force continuously to a button, inserting the button into a body part and stopping the rotation of the button when in proper position with respect to the body part. 35

4. The method of assembling buttons having a decoration thereon, with seamed body parts, which method comprises supporting a body part, applying a rotative force continuously to the button through the intermediation of a partial 40 vacuum, stopping the rotation of the button when in proper position with respect to the body part, and interlocking the button and the body part.

5. The method of assembling buttons with seamed body parts to provide closure caps, which 45 method comprises forming a projection on the button, holding the button by a partial vacuum, applying a rotative force continuously to the button and utilizing said projection to stop the button when in proper position with respect to a body 50 part in opposition to said partial vacuum and said rotative force.

6. The method of assembling buttons with seamed body parts, which method comprises forming a projection on the button, applying a 55 rotative force continuously to said button, utilizing said projection to stop the button in proper registry with the body part, and interlocking said button and body part.

7. The method of turning a button to position 60 the button with respect to a seamed body part, which method comprises forming a projection on the button, inserting the button into the body part, applying a force tending to rotate the button continuously, and engaging the projection to 65 stop the button and to hold it in proper registry with the seamed body part.

8. The method of turning a button to position 70 the button with respect to a seamed body part, which method comprises forming a projection on the button, applying a force tending to rotate the button continuously, holding the button in position by a vacuum, and engaging the projection to stop the button when the projection is in proper registry with the seam of the body part. 75

9. The method of turning a button into proper registry with a seamed body part, which method comprises applying a force tending to rotate a button continuously, and utilizing the seam of the body part to stop the button in proper registry with the body part.

10. The method of assembling a button and a seamed body part, which method comprises providing a button with a recess in the periphery thereof, inserting the button while applying a force tending to rotate the button, and utilizing the seam of the body part to engage the recess in the button to stop the button in proper registry with the body part.

11. In a device of the class described, the combination of a member for fitting into and supporting a tubular body part, rotating means for holding a button by vacuum and for rotating said button, means for stopping the rotation of said button when in proper registry with the body part without stopping the rotation of said first means, and means for permanently securing said button to the body part.

12. In a device of the class described, the combination of a support for a body part, means for rotating a button, means for stopping the rotation of said button without stopping the rotation of said first means, and means for reciprocating said rotating means axially thereof to insert the button into the body part.

13. In a device of the class described, means for holding a body part, a mandrel for supporting a button and for inserting the button into the body part, said button being retained on said mandrel by vacuum, means for rotating said mandrel with the button thereon, and means adjacent to the outer periphery of the button for stopping the rotation of said button without stopping the rotation of said mandrel.

14. In a device of the class described, means for holding a body part, a mandrel for supporting a button, vacuum means for retaining said button on said mandrel, means for rotating said mandrel about its longitudinal axis to position said button with respect to the body part, and means for seaming said body part to said button.

15. In a device of the class described, means for holding a body part of a cap, a mandrel for supporting a button of a cap, said button being retained on said mandrel by vacuum, means for continuously rotating said mandrel to rotate the button about its center, and means adjacent the outer periphery of the button for stopping the rotation of said button without stopping the rotation of said mandrel.

16. In a device of the class described, the combination of a support for body parts of a tubular article, a guideway for buttons, a hollow member terminating adjacent said guideway, means for creating suction within said hollow member to engage one of the buttons and to hold it thereon, means for moving said hollow member longitudinally to insert the button held thereon into the body part and means for rotating said hollow member about its longitudinal axis to turn the button into proper registry with the body part of an article.

17. In a device of the class described, the combination of a support for body parts of a cap, a guideway for buttons, a member terminating adjacent said guideway, means for creating suction within said member to hold the button thereon, means for rotating said member, said button having a projection thereon, and means for engaging the projection to stop the rotation

of the button when turned into proper registry with the body part of a cap.

18. In a device of the class described, the combination of a support for a body part, a hollow member for inserting a button into the body part, means for creating a suction within said hollow member to hold the button thereon, means for rotating said hollow member about its longitudinal axis to turn said button, and a pivotally mounted member for engaging said button when turned into proper registry with a body part to hold said button against further rotation.

19. In a device of the class described, a support for a body part, a guideway for buttons, a member adapted to engage and hold a button delivered through said guideway, means for rotating said member continuously, said button having a projection therein, means for engaging said projection to stop the rotation of said button without stopping the rotation of said member, and means for reciprocating said member to insert the button into the cap without stopping the rotation of the member.

20. In a device of the class described, the combination of a turret adapted to receive body parts and position them at an assembly station, a mandrel for engaging and holding a button in alignment with the body part, means for rotating said mandrel continuously to turn the button into proper registry with the body part, means for engaging the button to hold it against rotation when in proper registry, and means for reciprocating the mandrel to insert the button into the body part.

21. In a device of the class described, the combination of a turret adapted to receive body parts and position them at an assembly station, a mandrel for engaging and holding a button in alignment with the body part, means for rotating said mandrel continuously to turn the button into proper registry with the body part, means for engaging the button to hold it against rotation when in proper registry, means for reciprocating the mandrel to insert the button into the body part, and means for connecting said button and body part by an interfolded seam.

22. The method of assembling decorated cover parts with body parts, which method comprises applying a force tending to rotate the cover part continuously about its center, holding the cover part against rotation when turned into proper position with respect to said body part, and securing said cover part to said body part.

23. The method of assembling articles comprising a decorated cover part and a substantially tubular body part, which method comprises forming a projection on the cover part, applying a rotative force continuously to said cover, tending to rotate the button continuously, utilizing said projection to stop the cover part when in proper registry with the body part, and interlocking said cover part and body part.

24. In a device of the class described, the combination of a support for body parts of a cap, a chute for buttons, a hollow member terminating adjacent to the lowermost button in said chute, means for creating suction within said hollow member to hold a button thereon, means for moving said hollow member forward to insert the button into a body part of a cap, means for rotating said hollow member to properly position the button with respect to the body part, and means for securing the button to the body part.

25. The method of assembling a button having

a top portion with a seamed body part to provide a two-piece closure cap, which method comprises, engaging the top portion of a button, inserting a button into a seamed body part, applying a force tending to rotate the button continuously and stopping the rotation of the button when in proper position.

26. In a device for assembling parts of a closure cap, the combination of a support for the

body part of a cap, continuously rotating means adjacent to said support for inserting a button into the body part and for rotating the button while in the body part, and means associated with the button for stopping the rotation of the button when the button is in proper registry with the body part, without stopping the rotation of said rotating means.

JOHN C. GIBBS.
